UNITED STATES PATENT OFFICE.

LEWIS E. McCONNELL, JR., OF MONTCLAIR, NEW JERSEY, ASSIGNOR TO THE W. F. POWERS COMPANY, OF NEW YORK, N. Y., A CORPORATION OF NEW YORK.

ADVERTISING DEVICE.

Application filed October 11, 1928. Serial No. 311,795.

This invention relates to a display sign or placard adapted to be attached to the under side of the top of a glass show case or the like to advertise or call attention to some article in the case adjacent the card.

The invention is illustrated in the accompanying drawing, in which

Figure 1 is a perspective view of a part of a show case with my improved card attached thereto.

Figure 2 is a section through the case and the center of the card showing how the card hangs away from the top of the case.

Figure 3 is a similar view showing the card as it is finally positioned.

Figure 4 is a plan view of the card, and

Figure 5 shows the card in a flat position.

In the drawing, 1 and 2 represent respectively the top and front of a glass show case. The advertising card 3 may be made from a flat cardboard in the general shape as shown in Figure 5. It is folded along the line 4 to form a right angle, one leg 5 being adapted to have advertising matter placed thereon, as shown in Figure 1, and the other leg 6 having a slotted orifice 7 adapted to fit over the neck 8 of a rubber vacuum cup 9 whereby the card may be at-

tached to the under side of the top of the show case. When the card is so attached to the underside of the top of the show case, the display part 5 hangs vertically and in order to make it fit neatly up against the top plate and against the glass front of the case, 35 I provide a rear lip 10 in the form of a flange which may be folded up until its edge impinges on the under side of the glass top plate as shown in Figure 3. When this is done, the display leg 5 is held tight 40 against the glass front in a rigid upright position. Without this bracing rear part, the card may hang all awry, being neither vertical nor square with either the top or the front of the case.

45 I claim:—

The combination of a vacuum cup and a display sign adapted to be attached to the underside of a support, the sign having a vertical display portion and a horizontal 50 supporting portion, the latter having means of attachment to the vacuum cup and a flange at the rear edge adapted to bear against the underside of the support for the vacuum cup and hold the display portion 55 rigid.
